KEY HOLDER FOR A HANDBAG OR THE LIKE

Edward M. Davis, Brooklyn, N. Y.

Application November 30, 1950, Serial No. 13,204

Term of patent 3½ years

(Cl. D87—2)

To all whom it may concern:

Be it known that I, Edward M. Davis, a citizen of the United States and a resident of the city of Brooklyn, county of Kings, State of New York, have invented a new, original, and ornamental Design for a Key Holder for a Handbag or the like, of which the following is a specification, reference being had to the accompanying drawings, forming part hereof and in which:

Fig. 1 is a front elevational view of a key holder for a handbag or the like embodying my new design.

Fig. 2 is a side elevational view.

Fig. 3 is a bottom plan view.

Fig. 4 is a top plan view.

I claim:

The ornamental design for a key holder for a handbag or the like, substantially as shown,
EDWARD M. DAVIS.
